Primary Examiner — Katie Jane Stofko

(57) **CLAIM**

The ornamental design for a marshmallow confectionery, as shown and described.

DESCRIPTION

The patent or application file contains at least one drawing executed in color. Copies of this patent or patent application publication with color drawing(s) will be provided by the Office upon request and payment of the necessary fee.

FIG. 1.1 is a front, top and right side perspective view of a marshmallow confectionery showing my new design;

FIG. 1.2 is a top plan view thereof;

FIG. 1.3 is a bottom plan view thereof;

FIG. 1.4 is a front elevation view thereof;

FIG. 1.5 is a rear elevation view thereof;

FIG. 1.6 is a left side elevation view thereof;

FIG. 1.7 is a right side elevation view thereof;

FIG. 1.8 is a rear elevation view of a middle layer of the marshmallow confectionery shown separately for ease of illustration;

FIG. 1.9 is a top plan view of a top layer of the marshmallow confectionery shown separately for ease of illustration; and FIG. 1.10 is a front elevation view of a bottom layer of the marshmallow confectionery shown separately for ease of illustration.
